DESIGN FOR A CLOCK DIAL OR SIMILAR ARTICLE

Aaron Elkonin, Brooklyn, N. Y.

Application October 12, 1935, Serial No. 58,961

Term of patent 14 years

To all whom it may concern:

Be it known that Aaron Elkonin, citizen of U. S. S. R. and resident of Brooklyn in the county of Kings and State of New York, has invented new, original, and ornamental Design for a Clock Dial or Similar Article, of which the following is a specification, reference being had to the accompanying drawing, forming part thereof, in which,

The figure is a front view of a clock dial embodying my new design said design having no appreciable thickness.

I claim:

The ornamental design for a clock dial or similar article substantially as shown and described.

Dated, New York city, October 11, 1935.

AARON ELKONIN.
